UNITED STATES PATENT OFFICE.

FRANK T. WHEELER, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

CONDUIT-RECEPTACLE.

No. 825,995.

Specification of Letters Patent.

Patented July 17, 1906.

Application filed October 26, 1905. Serial No. 284,305.

To all whom it may concern:

Be it known that I, FRANK T. WHEELER, a citizen of the United States, and a resident of Plainville, in the county of Hartford and 5 State of Connecticut, (whose post-office address is Plainville, Connecticut,) have invented certain new and useful Improvements in Conduit-Receptacles, of which the following is a full, clear, and exact description, where- 10 by any one skilled in the art may make and use the same.

The invention relates primarily to receptacles or perhaps more properly sockets—that is, a receptacle containing contact members 15 arranged to connect an electric circuit through any device by inserting within the receptacle a plug-like member having suitable contacts and conductors.

It relates more particularly to what is 20 known in the art as a "waterproof" receptacle.

The objects of the invention are to provide 25 an insulating-receptacle having a small number of parts and with each of the various parts so associated and united as to produce a structure which will withstand great strains and hard usage without liability of disarrangement.

A still further object is to arrange the contact parts of the receptacle in such manner 30 that the attached conductors may be intimately and positively united with the contact parts before final assembly.

A still further object is to provide a receptacle adapted for conduit use.

Referring to the drawings, Figures 1, 2, 3, and 4 show in detailed vertical section the several parts unassembled. Fig. 5 is a central sectional view with the parts assembled. 40 Fig. 6 is a detail plan view of the insulating cup or receptacle.

It has been the common practice to use a shell of insulating material, molded or otherwise intimately united with a shell-like contact member forming one terminal of the circuit and a central contact member providing the terminal of opposite polarity. Ordinarily in such structures the central contact and the tubular or shell-like contact have 50 been independent one of the other.

It is one of the purposes of the present invention to combine the outer or shell-like contact and the central contact in a single

structure, to which the conductors may be firmly and positively applied, as by soldering, providing, of course, a suitable insulation between the two contact members. 55

In the accompanying drawings the numeral 1 denotes a base of insulating material having an upwardly-extending tubular portion 2 and integral lugs 3, by which the base or receptacle as a whole may be secured in place. 60

On diametrically opposite sides on the base 1 are openings 4 and 5, through which the conductors attached to the contact members (hereinafter described) are led out. It will be noted that these conductors project outwardly from the base 1 at a considerable distance above its point of attachment, 70 whereby insulation of said conductors from a metallic or other conducting-support is insured.

Within the insulator 1 and at some little distance above the bottom of its central bore 75 is formed the ledge 6, which forms a stop and support for the tubular contact member 7 with its contained central contact. One of the outlet-passages, as 4, is formed through the wall of this ledge, and as the parts are 80 brought together a space 8 is left between the bottom of the bore of the receptacle 1 and the contact-shell 7. An opening 9 is provided through the bottom of the base to its central bore, through which a suitable insulating material may be flowed to fill the space 8 and insure perfect insulation of the entering conductors and connected contacts. 85

The contact-shell 7, as herein shown, consists of a screw-threaded shell, though this 90 form may be varied to suit the exigencies of any particular case, and a straight plug or screw-threaded plug may be used by varying the form of the shell 7.

In the lower edge of the shell is secured a 95 button of insulating material 10, recessed at its center, as at 11, to receive the central contact-stud 12. As shown in cross-section, this insulating-button is substantially in the form of a half-oval and on its bottom has a recess 100 13 for purposes hereinafter defined. This insulating-button is inserted in the end of the tubular member 7, and the lower edge of the tube is then spun over the bottom of the button, thereby uniting it and holding it firmly 105 in place on the bottom of the contact-shell.

The central contact-button 12 is of a suitable form to enter the opening 11 and has a head 14 and stud 15, which give it a firm bearing in the button 10. It has a central bore 16, into which may be introduced the end of the conductor 10^a, preferably held therein by soldering, and as the solder is flowed into the recess 13, formed about the opening 11, said solder will not only firmly unite the conductor and contact 12, but forming a "sprue" in the recess 13 will prevent disengagement of the button 10 and contact 12.

The second conductor is soldered to the shell 7, and thus all soldering operations may be performed while the shell, with its contained insulating-button 10 and central contact 12, is pulled out of the receptacle 1.

By pulling upon the conductors after they have been passed through the openings 4 and 5 the contact members will be firmly seated upon the ledge 6 within the receptacle, and thereupon the insulating material introduced through the opening 9 and filling the recess 8 will securely hold the parts and insulate them perfectly.

Obviously various forms of receptacle and contact members might be used, and the device might be materially changed as to detail without departing from the spirit or intent of the invention.

What I claim as my invention, and desire to secure by Letters Patent, is—

1. In combination with a base of insulating material, a tubular contact member having secured in one end an insulating-button of convex form with a concave recess in its lower side and a central contact member fitting within said button and having a part projecting therethrough and into the concave recess, substantially as described.

2. In combination in a receptacle, a base of insulating material having a central bore, a ledge formed on the inner wall of said bore, conductor-openings passing through the walls of the receptacle below the ledge, and contact members supported by the ledge with one contact member resting upon the ledge.

3. In combination in a receptacle, a base of insulating material having a central bore, a ledge formed on the inner wall of said bore, conductor-openings passing through the walls of the receptacle below the ledge, a contact member resting upon the ledge, a coöperating contact supported by the first-named contact member and means for introducing

an insulating material through the bottom of the receptacle.

4. In a receptacle, in combination with a tubular and central contact, a base of insulating material surrounding said parts and provided with a ledge or stop forming a seat for said parts with a recess below the ledge, conductor-openings passing through the walls of the base of insulating material below the ledge, and insulating material filling the recess.

5. In combination in a receptacle, a base of insulating material provided with an internal stop, a tubular contact member located within said base and seated upon the stop, having secured thereto an insulating-button with an opening therethrough, a central contact member fitted within the upper side of said opening, having a tube extending therethrough to receive a conductor and means for uniting the conductor and central contact and simultaneously locking the contact and the insulating-button.

6. In combination in a receptacle, a tubular contact member having a bottom of insulating material, a contact opening through said bottom, a recess formed about said contact-opening on one side of the insulating-bottom to retain a mass of solder, a contact having a part adapted to project through the contact-opening into the recess and means including the solder and a conductor for firmly uniting the contact and insulating-bottom.

7. In combination in a receptacle, a base of insulating material having a central bore, a ledge or stop formed on the inner wall of said bore, conductor-openings passing through the walls of the receptacle below the ledge, a contact member resting on the ledge and forming a support for a coöperating contact member and the coöperating contact member.

8. In combination in a receptacle, a base of insulating material having a central bore, a ledge or stop formed on the inner wall of said bore, conductor-openings passing through the walls of the receptacle below the ledge, a contact member resting on the ledge and forming a support for a coöperating contact member and an insulating-button surrounding said coöperating contact member.

FRANK T. WHEELER.
